UNITED STATES PATENT OFFICE.

ROBERT R. MCCORMICK, OF CHICAGO, ILLINOIS.

PRINTING PRESS.

Application filed July 19, 1926. Serial No. 123,406.

This invention relates to printing presses such as are used to print large newspapers, for example, where numerous variations of page and section associations may be required to meet the conditions of practical newspaper production, which involves the utilization of different numbers and combinations of printing units, or couples, for different issues and editions and as may be required to accommodate growth and expansion of the paper. The invention contemplates in this regard the use of an infinite number of printing units arranged in a row and having appropriately interspersed folding mechanisms and perfecting devices associated therewith, as shown and described in my former Patent No. 1,581,132, and provides, in combination therewith, an arrangement of supplementary printing units and associated web turning and guiding mechanisms adapted to increase the capacity of the press, both as to total delivery and as to variety of combinations of printing units, rendering possible greater flexibility of page associations and groupings in sections of desired size and number.

To this end, the supplementary printing units and associated mechanisms are so related to the units, folders, etc., in the continuous line or row, as shown in my former patent, that the webs therefrom may be fed by devices provided for the purpose to particular or selected folders in the line, the arrangement preferably being such that the supplementary units are disposed laterally of the line in close proximity thereto and with their cylinders extending at right angles to those of the units in the line, the complete press, consisting of the main line and supplementary units, being divisible into a variable series of groups, the units of which feed their webs to a common folder without passing any other folder in the press.

It is also within the purview of the invention to so relate the outside units to those in the line that maximum capacity may be obtained with the smallest possible floor space, it being obvious that the item of floor space is a factor of considerable importance in the cost of production of newspapers in large cities where ground values are very high and adjacent space for expansion often unavailable.

Numerous other objects and advantages of the invention will be apparent as it is better understood from the following description,

which, taken in connection with the accompanying drawings, discloses a preferred embodiment thereof.

Referring to the drawings,

Figure 1 is a largely diagrammatic view, in side elevation, of a printing press in which my invention is embodied, the same illustrating a variety of combinations of page and section associations which are made possible by the invention;

Fig. 2 is a top plan view of the apparatus shown in Fig. 1;

Fig. 3 is a view similar to Fig. 1, showing different combinations of printing units or couples and a different manner of use of the folding mechanisms;

Fig. 4 is an end elevation, also diagrammatic, of the press shown in the preceding figures; and

Fig. 5 is an enlarged sectional and elevational view of one of the groups of printing units and associated mechanisms, the group, as shown, comprising a double octuple.

In the illustrative embodiment of the invention shown on the drawings, the reference character 41 indicates a frame, which is relatively elongated and adapted to support the printing mechanism and associated devices, which will be presently described, said frame being supported upon posts 42 and preferably arranged to rest upon the floor of a press room beneath which, in a basement or sub-level, the paper rolls 43 are mounted, the latter, as shown, being arranged in groups of three upon reels carried by a shaft 44, which are journaled in uprights 45. A plurality of printing units or couples, numbered 1 to 30 in Fig. 3 of the drawings, are accessibly arranged upon the frame 41 and each thereof comprises impression cylinders 46 and 47 and printing cylinders 48 and 49, the web being adapted to be directed from a roll 43 in the basement over guiding rolls 51, 52 and 53, the latter being above the bed of the frame and being disposed centrally between the rollers 48 and 49 so that the web may be directed in either direction so as to be first acted upon by one printing cylinder or the other, as may be desired. The web, which is indicated by the reference character 54, after passing the guide roller 53, is fed between one printing cylinder and associated impression cylinder,

as clearly shown in Fig. 5 of the drawings, and thence downwardly around the other impression cylinder and upwardly between

the latter and the remaining printing cylinder, after which it is guided about a plurality of guide rolls 55, suitably arranged upon the frame and adapted to direct the printed web from the printing units or couples to the folders which are marked 1st to 7th, inclusive, on the drawings, these folders being arranged between certain of the printing units and on a common level therewith, the arrangement being such as to render possible the most effective grouping of the units to produce the page associations and section arrangement which I have found desirable in newspaper printing and as will herein-
 10 after more fully appear. The folders, like the printing units or couples, are only dia-
 grammatically shown, and it will be noted that, as shown, they comprise superimposed
 15 pairs of formers, indicated respectively by the reference characters 56 and 57, one or both of which may be utilized, the use of both pairs being illustrated in Figs. 1 and 5 of the drawings and the use of only one pair being illustrated in Fig. 3. It will be
 20 evident that when both pairs are used, a greater variety of section associations is possible, the sections formed in the upper formers being adapted to be interfolded with the sections formed in the lower formers in
 25 a widely varying arrangement as to numbers of sections and of pages in a section. The printing cylinders are ordinarily adapted to carry two plates circumferentially and four lengthwise, so that each printing couple is
 30 capable of producing sixteen separate pages, or eight pages when the plates are arranged two on, i. e., so that each sheet is duplicated in the couple. The results which may be obtained by different groupings of the units
 35 will be indicated at a later point in the description.

The part of the apparatus heretofore de-
 40 scribed is substantially the same as that shown in my prior patent above referred to, and I shall now proceed to describe the supplementary printing units and associated de-
 45 vices and to point out the manner in which they may be combined with the above-de-
 50 scribed mechanism to produce greater flexi-
 55 bility and capacity of the press. Said sup-
 60 plementary units are indicated, respectively, by the reference characters 31 to 40, in-
 65 clusive, the arrangement being such that two units may be associated with each group in a line when the latter are arranged in double sextuples, the addition of the laterally dis-
 70 posed units making of each group in this arrangement a double octuple, as shown in Figs. 1, 2 and 5 of the drawings. The webs
 75 58 are directed over properly arranged guid-
 80 ing rollers 55 and turning bars arranged above the printing units in the line, with the result indicated at 59 in Fig. 2, from
 85 which it will be apparent that the incoming web is turned from transverse to longi-

tudinal direction and directed to the folder of the group with which the unit is associated. As will be apparent from viewing Fig. 4, the laterally disposed units are similar in construction to those arranged in the line, but the printing and impression rolls are disposed longitudinally of the line instead of transversely, as in the case of the other units. The webs from the several units associated with a particular folder are directed over a common guide roller 61, and it is to be understood that suitable slitting and delivery devices are provided so that the papers are rapidly formed and delivered from the press to appropriate points for mailing or local distribution.

It will be noted that the folders are ar-
 90 ranged between the 3d and 4th, the 9th and 10th, the 12th and 13th, the 15th and 16th, the 18th and 19th, the 21st and 22nd, and the 27th and 28th units, and that when grouped uniformly, as shown in Figs. 1, 2 and 5, the webs from three units on each side of the 1st, 2nd, 4th, 6th and 7th folders, to-
 95 gether with the webs from the associated laterally disposed units, are directed into the folders indicated. Suitable driving mech-
 100 anism for the printing units and associated devices is, of course, provided, though not shown on the drawings since the construction and operation of the mechanism dia-
 105 grammatically illustrated will be well un-
 110 derstood by those skilled in the art.

Great flexibility of page association, as well as greatly enlarged capacity, is pro-
 115 vided by the press of my invention. With the units grouped in the double octuple ar-
 120 rangement shown in Figs. 1, 2 and 5 of the drawings, each group is capable of produc-
 125 ing two complete papers of sixty-four pages each, which may each be associated in sec-
 130 tions of thirty-two pages, or, when both up-
 135 per and lower formers are used, any eight-
 140 page variation thereof. In Fig. 3, I have
 145 illustrated a variety of different aggroup-
 150 ments, the first and last groups each com-
 155 prising six units in the line and two of the laterally disposed units, making double octuples, the second and third groups each comprising three units in the line and one
 160 from outside, making octuples, the fourth group comprising three units in the line and two outside, making a decuple, the fifth group comprising five units in the line and one outside, making a double sextuple, and the sixth group comprising four units in the line and one outside, making a decuple. Manifestly, various other aggroupments are possible, the number being increased by
 165 omitting certain units if desired, and if single or three-quarter width webs, instead of double width webs, are used, still greater flexibility is rendered possible, inasmuch as the sections may be arranged in variations of two or four, instead of eight pages.

The increased flexibility of the press of the present invention is indicated by the fact that the following aggroupments of units are provided for the first time, so far as I am aware, with the result that the capacity of the press not only is increased from 48 to a 64 page limit, but the range of variation within this limit is correspondingly increased. As heretofore stated, the press, with the units grouped in the double-octuple arrangement shown in Figs. 1, 2 and 5 of the drawings, is capable of producing per group two complete papers of 64 pages each. If one of the units of each of the groups, as shown in said Figs. 1, 2 and 5, be left idle, a seven-unit grouping is obtained, with the result that each group produces two complete papers of 56 pages each, which is also a novel result of the present invention. Manifestly, the units of the press, which are arranged in tandem, are capable of division into a succession of equal groups of four or five or six printing units, as illustrated in Figs. 1, 2 and 3 of my prior Patent No. 1,581,132, and by the use of the present invention the production of the press may be still further varied by directing the webs from one or more of the units disposed outside the line to the folder of a particular group in the line without changing the grouping of the tandem units of the press. Thus a printing plant constructed in accordance with my invention as specifically illustrated is capable of aggroupment of the units so that a succession of eight, seven, six, five or four equal groups may be selectively utilized, which result is not possible with the press illustrated in my prior patent above referred to, or with any other press known prior to my invention, so far as I am aware.

Referring to Fig. 5, it will be noted that certain of the webs fed to the upper pair of formers are divided before reaching the common guide roller 61 and the separate web portions 62 and 63 are arranged in superimposed relationship by suitable turning bars and spaced guide rollers 55 interposed between the slitter and said common guide roller 61, this arrangement indicating still further possibilities of flexibility in the page and section associations.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A flexible unit printing press, comprising a row of printing units and folders arranged in a line on a common level and

divisible into a plurality of groups the printing units of which are associated with a single folder, a plurality of printing units disposed laterally of said line and individually associated with particular groups in the line, and means for directing the webs from said laterally disposed units to the folders of the groups with which they are associated. 70

2. A flexible unit printing press, comprising a row of printing units and folders arranged in a line on a common level and divisible into a plurality of groups the printing units of which are associated with a single folder, a plurality of printing units disposed laterally of said line and individually associated with particular groups in the line, and means for directing the webs from said laterally disposed units to the folders of the groups with which they are associated, a plurality of said laterally disposed units being associated with each group. 75

3. A flexible unit printing press, comprising a row of printing units and folders arranged in a line on a common level and divisible into a plurality of groups the printing units of which are associated with a single folder, a plurality of printing units disposed laterally of said line and individually associated with particular groups in the line, and means for directing the webs from said laterally disposed units to the folders of the groups with which they are associated, a plurality of said laterally disposed units being associated with each group. 90

4. A flexible unit printing press, comprising a row of printing units and folders arranged in a line on a common level and divisible into a plurality of groups the printing units of which are associated with a single folder, a plurality of printing units disposed laterally of said line and individually associated with particular groups in the line, and means for directing the webs from said laterally disposed units to the folders of the groups with which they are associated, said line and associated printing units being divisible into a succession of groups each containing eight units and one folder. 105

5. A flexible unit printing press, comprising a row of printing units and folders arranged in a line on a common level and divisible into a plurality of groups the printing units of which are associated with a single folder, a plurality of printing units disposed laterally of said line and individually associated with particular groups in the line, and means for directing the webs from said laterally disposed units to the folders of the groups with which they are associated, said line and associated printing 110

units being divisible into a succession of groups each containing eight units and one folder to which the webs from said units may be fed without passing any other folder in the line.

6. A flexible unit printing press, comprising a row of printing units and folders arranged in a line on a common level and divisible into a plurality of groups the printing units of which are associated with a single folder, a plurality of printing units disposed laterally of said line and individually associated with particular groups in the line, and means for directing the webs from said laterally disposed units to the folders of the groups with which they are associated, the printing units each comprising a printing couple and the line and associated units being adapted to be divided into a succession of equal groups each comprising a double octuple.

7. A flexible unit printing press, comprising a row of printing units and folders arranged in a line on a common level and divisible into a plurality of groups the printing units of which are associated with a single folder, a plurality of printing units disposed laterally of said line and individually associated with particular groups in the line, and means for directing the webs from said laterally disposed units to the folders of the groups with which they are associated, said line and associated printing units being divisible into a succession of groups each containing six line units, two associated units and one folder, the webs from all the printing units of any group being fed to the single folder of said group without passing any other folder in the line.

8. A flexible unit printing press, comprising a row of printing units and folders arranged in a line on a common level and divisible into a plurality of groups the printing units of which are associated with a single folder, a plurality of printing units disposed laterally of said line and individually associated with particular groups in the line, and means for directing the webs from said laterally disposed units to the folders of the groups with which they are associated, the printing units each comprising a printing couple and the line and associated units being adapted to be divided into a succession of equal groups each comprising a double octuple, the webs from all the printing units of any group being fed to the single folder of said group without passing any other folder in the line.

9. A flexible unit press comprising a series of printing units accessibly arranged in spaced apart relation on the same printing level, a web supply for each unit, a plurality of folding units disposed on said printing level, said folding units being spaced apart and disposed relatively to said printing units so that the row of printing units is selectively divisible into a succession of equal groups of four, or five, or six printing units, each selected group containing but a single folding unit and all of the printing units of a

so that the series of printing units is selectively divisible into a plurality of equal groups of six, or seven, or eight printing units, each selected group containing but a single folding unit and all of the printing units of a group of any selected series of groups feeding their webs to the folding unit of that group.

10. A flexible unit press comprising a series of printing units accessibly arranged in spaced apart relation on the same printing level, a web supply for each unit, a plurality of folding units disposed on said printing level, said folding units being spaced apart and disposed relatively to said printing units so that the series of printing units is selectively divisible into a plurality of equal groups of eight printing units, each selected group containing but a single folding unit and all of the printing units of a group of any selected series of groups feeding their webs to the folding unit of that group.

11. A flexible unit press comprising a series of printing units accessibly arranged in spaced apart relation on the same printing level, a web supply for each unit, a plurality of folding units disposed on said printing level, said folding units being spaced apart and disposed relatively to said printing units so that the series of printing units is selectively divisible into a plurality of equal groups of seven printing units, each selected group containing but a single folding unit and all of the printing units of a group of any selected series of groups feeding their webs to the folding unit of that group.

12. A flexible unit press comprising a series of printing units accessibly arranged in spaced apart relation on the same printing level, a web supply for each unit, a plurality of folding units disposed on said printing level, said folding units being spaced apart and disposed relatively to said printing units so that the series of printing units is selectively divisible into a plurality of equal groups of eight or less printing units, each selected group containing but a single folding unit and all of the printing units of a group of any selected series of groups feeding their webs to the folding unit of that group.

13. In combination, a flexible unit press comprising a row of printing units accessibly arranged in spaced apart relation on the same printing level, a web supply for each unit, a plurality of folding units disposed on said printing level, said folding units being spaced apart and disposed relatively to said printing units so that the row of printing units is selectively divisible into a succession of equal groups of four, or five, or six printing units, each selected group containing but a single folding unit and all of the printing units of a

group of any selected series of groups feeding their webs to the folding unit of that group, and a plurality of printing units disposed outside said row and feeding their webs to said folding mechanisms.

14. In combination, a flexible unit press comprising a single row of printing and folding units accessibly arranged in spaced apart relation on the same printing level, a 10 web supply for each printing unit, said folding units being distributively arranged in said row and between said printing units so that the row of printing units is selectively divisible into a succession of equal groups 15 of four, or five, or six printing units, each selected group containing but a single folding unit and all of the printing units of a group of any selected series of groups feeding their webs to the folding unit of that 20 group whereby no web from a printing unit is compelled to travel across an idle folding unit, and a plurality of printing units disposed outside said row and feeding their webs to said folding mechanisms.

25 15. In combination, a flexible press for printing newspapers and the like comprising a supporting frame, thirty printing couples spaced thereon with their cylinders disposed transversely of and in a single row 30 longitudinally of the frame and in a common plane, a plurality of folding mechanisms disposed on said frame in said plane and intermediate certain of said couples, said folding mechanisms being disposed between 35 the third and fourth couples, and between the ninth and tenth couples, and between the twelfth and thirteenth couples, and between the fifteenth and sixteenth couples, and between the eighteenth and nineteenth couples, 40 and between the twenty-first and twenty-second couples, and between the twenty-seventh and twenty-eighth couples, guide-rolls on said frame for directing the webs from said couples to the folding mechanisms, and a plurality of printing units 45 disposed outside said row and feeding their webs to said folding mechanisms.

16. In combination, a flexible press for

printing newspapers and the like, comprising a supporting frame, thirty printing 50 couples disposed in spaced relation in a common printing level thereon with their cylinders disposed transversely of and in a single line or row longitudinally of the frame in the printing level and, pairs 55 of formers disposed on said frame intermediate certain of said couples, said pairs being disposed between the third and fourth couples, and between the ninth and tenth couples, and between the twelfth and thirteenth couples, and between the eighteenth and nineteenth couples, and between the twenty-first and twenty-second couples, and between the twenty-seventh and twenty-eighth couples, and guide rolls on said frame, 60 said guide rolls and pairs of formers being constructed and arranged to direct the webs from certain of said couples to one or both of the formers of a pair or to one or both of said formers of said pairs, and a plurality 70 of printing units disposed outside said row and feeding their webs to said folding mechanisms.

17. A flexible unit printing press, comprising a row of printing units and folders arranged in a line on a common level and divisible into a plurality of groups the printing units of which are associated with a single folder, a plurality of printing units disposed laterally of said line and individually associated with particular groups in the line, and means for directing the webs from said laterally disposed units to the folders of the groups with which they are associated, said line and associated printing 80 units being divisible into a succession of groups each containing eight units and one folder, and the press containing forty units whereby five groups of eight units, or a correspondingly greater number of smaller 90 groups into which the press may be divisible, may be selectively utilized.

In witness whereof, I hereunto subscribe my name to this specification.

ROBERT R. McCORMICK.
